Primary Examiner — John Windmuller*Assistant Examiner* — Steven J Czyz(74) *Attorney, Agent, or Firm* — Dunlap Bennett & Ludwig PLLC(57) **CLAIM**

The ornamental design for a spherical object holder, as shown and described.

DESCRIPTION

FIG. 1 is a perspective view of a spherical object holder, showing my new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines showing a spherical object in FIG. 1 depicts environmental subject matter that forms no part of the claimed design.

1 Claim, 4 Drawing Sheets(56)
